UNITED STATES PATENT OFFICE

ARTHUR LENTZ, OF DUSSELDORF, GERMANY

COMBINED SORTING AND FEEDING MACHINE

Application filed May 23, 1927, Serial No. 193,652, and in Germany May 28, 1926.

The object of the present invention is a machine which serves simultaneously for the sorting and transporting, loading etc., of ashes, rubbish, stones, sand and similar materials. It combines therefore two working processes which have formerly been separately effected into a single process, whereby considerable saving in labour-cost, time and power are effected.

10 The essence of the invention consists in an electric motor being centrally rigidly connected with a main body inclined to the horizontal, the shaft of which motor is coupled, either permanently or easily disconnectably, with a disc fly wheel provided with beaters, which sorts according to size and feeds further the material falling through an inclined or horizontal easily changeable sieve.

Figures 1 and 2 of the accompanying drawing show the machine in vertical section and in front view respectively.

Figure 3 shows in plan the thrower casing with the flywheel and beaters.

Figure 4 shows an alternative construction of coupling of the fly wheel with the flange of the motor shaft.

In the drawings *a* is the casing of the machine, *b* the flange on the casing to which the electric motor is secured, *c* is the motor flange, *d* is the flange fast on the motor shaft, *e* the thrower disc with the beaters *f* thereon, *g* is the shear pin coupling the thrower disc with the motor shaft flange, *h* is the changeable sieve and *i* the thrower casing.

35 The operation is as follows: The material to be sorted and fed is thrown as indicated by the arrows, through the sieve which has its mesh chosen according to need; it enters the thrower casing and is thrown by the thrower disc with great speed out of the casing opening into the air or into a conducting pipe into a wagon or container.

What I claim is:—

1. A combined sorting and feeding device comprising a casing, a motor mounted within said casing, a shaft in said motor, said motor and shaft being inclined to the vertical, a material receiving chamber located on said casing and into which said shaft extends, a material throwing member mounted on said

shaft within said material receiving casing, the axis of said material receiving chamber and said material throwing member being concentric with said shaft and likewise inclined to the vertical, said material receiving casing being provided with an inlet located adjacent to the lower side thereof and with an outlet located adjacent the upper side of said casing.

2. A combined material sorting and feeding device comprising a hollow casing, an inwardly extending annular flange within said casing, the plane of said flange being at an angle to the vertical, a motor, means for securing said motor to said annular flange, 60 a shaft in said motor, a material receiving chamber located on said casing into which said motor shaft extends, a material throwing member mounted on said shaft within the material receiving chamber and outlet and inlet ports provided on said material receiving chamber.

3. A combined material sorting and feeding device comprising a hollow casing, an inwardly extending annular flange within 75 said casing, a motor, means for securing said motor to said annular flange, a shaft on said motor, a material receiving chamber located on said casing into which said motor shaft extends, a material throwing member mounted on said shaft with said material receiving chamber and outlet and inlet ports provided on said material receiving chamber.

In testimony whereof I have signed my name to this specification.

ARTHUR LENTZ.
